[57] ABSTRACT

A Gatling type gun includes a plurality of bolts and respective cross-slides, each of which is cam controlled and entirely encircles the bolt in the lock position.

BOLT LOCKING SYSTEM

BACKGROUND OF THE INVENTION

1. Field of the Invention

This invention relates to automatic and semiautomatic guns having a reciprocating bolt, and is especially adapted to multibarreled guns of the Gatling gun type.

2. Description of the Prior Art

The literature of machine guns is quite extensive. An excellent survey of locking systems is found in *The Machine Gun, Volume IV*, by George M. Chinn, Bureau of Ordnance, Department of the Navy, published by the Superintendent of Documents, U. S. G. P. O. 1951. An exemplary disclosure of the modern conventional Gatling gun is found in U. S. Pat. No. 2,849,921 issued to H. McC. Otto on Sept. 2, 1958 in which the bolt is rotated within the receiver to interengage locking lugs in the receiver. In U. S. Pat. No. 3,380,343 issued to R.E. Chiabrandy on Apr. 30, 1968 the bolt is carried by the receiver to engage a locking lug in the housing.

BRIEF SUMMARY OF THE INVENTION

It is an object of this invention to provide increased cross-sectional bolt locking circumference and area.

It is a further object of this invention to provide extended track guidance for the bolt for the full length of its reciprocation.

It is a yet further object of this invention to provide a lock which accomplishes its locking action through less movement and work, and which is of simple construction, thereby facilitating manufacture, assembly and maintenance.

A feature of this invention is a cross slide which is cam controlled and which entirely encircles the bolt.

BRIEF DESCRIPTION OF THE DRAWING

These and other objects, features and advantages of the invention will be apparent from the following specification thereof, taken in conjunction with the accompanying drawing in which:

FIG. 1 is a view in longitudinal cross-section of a bolt and locking system embodying this invention, showing the bolt unlocked;

FIG. 2 is a view in transverse cross-section of the system of FIG. 1 taken along the plane II-II;

FIG. 3 is a view in longitudinal cross-section of the system of FIG. 1 showing the bolt locked; and

FIG. 4 is a view in transverse cross-section of the system of FIG. 3 taken along the plane IV-IV.

THE PREFERRED EMBODIMENT

The embodiment of this invention herein shown and described is as incorporated in an otherwise conventional Gatling type gun, of the type disclosed in U. S. Pat. No. 3,380,343, supra, wherein the main cam is in a stationary housing, and the bolts are carried in a rotating receiver. A similar embodiment of this invention is also shown and described in U. S. Pat. application Ser. No. 76,077 filed concurrently herewith, wherein the main cam is in a rotating housing, and the bolts are carried in a stationary receiver, to which reference should be made for a more complete disclosure of the gun.

A bolt assembly 10 including a bolt body 12, a bolt face 14, extractor lugs 16, and a cam follower 18 is

disposed for reciprocation in a groove 20 in a receiver 22. The groove is aligned with a chamber 24 which is here shown as part of the receiver but which might conventionally be formed as part to the barrel, not shown, which is fixed into the receiver. The receiver is disposed in a housing 26 having a quasielliptical cylindrical cam slot 28 and an annular cam slot 30. There is relative rotation between the receiver and the housing.

Two longitudinal tracks 32 are fixed, as by machine screws, not shown, to the receiver and overlie the groove 20 and extend into two respective longitudinal slots 34 in the bolt body to provide longitudinal guidance for the bolt. The bolt cam follower 18 rides in the housing cam slot 28 and serves to reciprocate the bolt from an aft loading and ejection position to a forward locking and firing position.

A substantially annular slot 36 is formed into the periphery of the bolt body. A substantially U-shaped lock segment 38 rides in the bolt annular slot. The slot may have two opposed flat surfaces 40, 42, an inner arcuate surface 44, and an outer arcuate surface 46. The lock segment has two opposed flat surfaces 47, 48 and an arcuate surface 50, and two opposed cut-outs 52, 54 to accomodate the tracks 32.

A cross-slide 56 is disposed in a transverse slot 57 in the receiver and has a hole 58 configured to mate with and receive the lock segment 38 and the bolt body, and a cam follower 60 which rides in the housing cam slot 30. When the cross-slide 56 is in its centripetal position, as shown in FIG. 1, the lock segment is within the cross-section of the bolt body, and the bolt body is free to slide through the hole 58. When the cross-slide 56 is in its centrifugal position, caused by a rise in the cam slot 30, as shown in FIG. 3, the lock segment 38 has been partially raised out of the bolt annular slot 36 to enter into the receiver transverse slot 57, while the cross slide 56 has entered the bolt annular slot 36. It will be noted that the tracks 32 are interrupted in the plane of the cross-slide to permit reciprocation of the slide. The bolt body is now locked to the receiver by the combined lock segment and cross slide, around the full periphery of the bolt.

In operation, the round is handed to the bolt when the bolt is in its maximum aft position with the extractor lugs engaging the extractor rim of the case of the round. The cam slot 28 brings the bolt forward along the guide tracks together with the locking segment, 50 through the intermediate position shown in FIG. 1, until the bolt is fully forward with the round fully chambered, in the position shown in FIG. 3, with the locking segment aligned with the cross-slide. The rise in the cam slot 30 shifts the cross-slide centrifugally together with the locking segment, to lock the bolt in the receiver. The round R may be fed by a suitable mechanism not shown here, but shown in U. S. Pat. application Ser. No. 76,077 supra. The fall in the cam slot 30 shifts the cross-slide centripetally, together with the locking segment, to unlock the bolt. The cam slot 28 brings the bolt aft, extracting the fired case, along the guide tracks, together with the locking segment, until the bolt is fully aft to eject the fired case.

While preferred embodiments of this invention have been shown and described, it will be appreciated that other embodiments will become apparent to those skilled in the art upon reading this disclosure, and,

therefore, the invention is not to be limited by the disclosed embodiments, except as required by the hereto appended claims.

What is claimed is:

1. A bolt assembly for a firearm comprising:
a receiver having a lateral groove and a longitudinal groove therein;
a bolt, disposed in said receiver longitudinal groove and reciprocable between a load and a chamber position therein, and having a peripheral groove 10 therein;
a cross-slide, disposed in said receiver lateral groove and movable between an unlock and a lock position therein, and having an aperture therein defined by an interior wall adapted to clear said bolt when in said lock position and to engage said bolt peripheral groove when in said lock position; and
a U-shaped lock segment disposed in said bolt peripheral groove; 20
whereby, when said bolt is in its chamber position and said cross-slide is in its lock position engaged in said bolt peripheral groove, said lock segment is shifted by said cross-slide partially out of said bolt peripheral groove and partially into said receiver lateral groove, the combination of said cross-slide and said lock segment thereby providing 360° of lock around said bolt.
2. A bolt assembly according to claim 1 further including: 30
a first rotary cam coupled to said cross-slide and adapted to move said cross-slide to and between its lock and unlock positions.
3. A bolt assembly according to claim 2 further including: 35
a second cam coupled to said bolt and adapted to move said bolt to and between its load and chamber positions.
4. A bolt assembly according to claim 3 further including: 40
cam control means coupled to said first and second

cams for operating said cams in synchronism.

5. A gun comprising:

- a receiver having a plurality of chambers fixed thereto in an annular row, and a like plurality of lateral grooves and longitudinal grooves, a respective lateral groove and a longitudinal groove aligned with each chamber;
- a like plurality of bolts, each disposed in a respective longitudinal groove and reciprocable between a load and a chamber position therein, and having a peripheral groove therein;
- a like plurality of cross-slides, each disposed in a respective lateral groove and movable between an unlock and a lock position therein, and having an aperture therein adapted to clear said respective bolt when in said lock position and to engage said bolt peripheral groove when in said lock position; and
- a like plurality of U-shaped lock segments, each disposed in a respective bolt peripheral groove; whereby, when said respective bolt is in its chamber position and said respective cross-slide is in its lock position engaged in said bolt peripheral groove, said respective lock segment is shifted by said cross-slide partially out of said bolt peripheral groove and partially into said receiver respective lateral groove, the combination of said cross-slide and said lock segment thereby providing 360° of lock around said bolt.
6. A gun according to claim 5 further including:
a first rotary cam coupled to said plurality of cross-slides and adapted to move each of said cross-slides in sequence to and between its lock and unlock positions.
7. A gun according to claim 6 further including:
a second cam coupled to said plurality of bolts and adapted to move each of said bolts to and between its load and chamber positions.
8. A gun according to claim 7 further including:
cam control means coupled to said first and second cams for operating said cams in synchronism.
